ERSKINE RAMSAY, OF BIRMINGHAM, ALABAMA

METHOD AND APPARATUS FOR MINING DOUBLE OR PARTED SEAMS

Application filed June 26, 1931. Serial No. 546,997.

My invention relates to an improved method of and apparatus for mining and particularly, though not exclusively, for the mining of coal seams, wherein by reason of the presence of a "middleman" or slate parting formed between relatively thick or thin seams of coal, a condition heretofore regarded as commercially unworkable has resulted because the coal seams above and/or below the middleman could not be profitably worked, due to the large amount of rock to be handled composing the middleman, rendering the seam unworkable by present methods.

My invention contemplates an improved method for mining such seams which will be commercially practical and economical, and to this end I propose to conduct the coal mining operations of both coal seams with the middleman not molested or handled but left in position and to support the roof by two superimposed tiers of timbers or supports which are maintained in vertical transverse alignment one tier above and the other below the middleman. By this arrangement the middleman is left interposed as a "filler in" between the upper and lower sets of props or timbers and is supported by them for some distance back from the face but is permitted to fall with the roof behind the timbers as and when they are set forward together in following the advancing face of both upper and lower coal seams.

A further distinctive feature of my mining method is the utilization of a continuous conveyor with its upper flight traveling along over the middleman adjacent to and parallel to the upper face being mined and its lower flight traveling in the same relation to the lower face along but in reverse direction on the floor of the mine, thereby providing only a single conveying flight operating at each level and in opposite directions which permits the contemporaneous loading of cars in different entries from both seams by one conveyor.

My invention also contemplates adapting the single conveyor to be kept close to the faces being mined so it receives the coal as it falls by gravity onto the conveyor and loads

the coal as mined directly into the mine cars at opposite ends of the face being worked.

My invention also has the advantage of enabling the material mined in the two seams to be kept separate and loaded into different conveying or haulage means. This is especially important when the coal in one seam is better than, or suitable for a different use from that in the other seam.

Suitable means for carrying my improved method into effect is illustrated in the accompanying drawings which form a part of this specification, and in which:—

Fig. 1 shows a vertical cross sectional view of a mine working, taken in a vertical plane normal to the working faces; and

Fig. 2 is a cross sectional view taken along the line II—II of Fig. 1.

Similar reference numerals refer to similar parts throughout the drawings.

I have chosen to illustrate my invention as applied to the mining of coal, but it will be readily understood by those skilled in the art that it may be adapted to mining other minerals where conditions indicating its use exist.

In the drawings I have shown a condition which is often encountered in coal mines, particularly in Alabama, where we have an upper coal seam 5 divided from a lower coal seam 6 by a "middleman" or interposed rock or slate parting 7 of such thickness that if it be shot down with the coal as is present day practice it renders the mining unprofitable today in many cases by reason of the amount of rock or slate that it introduces into the coal and that must be picked out and loaded in cars and sent out or thrown back in the gob by the miners. Such conditions are often found to prevail where the coal is of very high grade and the mine operators would gladly mine the thin seams such as 5 and 6 if a practical method of mining could be devised which would eliminate the handling of the rock in the middleman and avoid shooting it down with the coal.

I have conceived that this can be done in the following manner, it being understood that the seams to be worked may form parts of

one seam or they may be different seams and of different minerals.

I propose to leave the middleman in position during the mining operation and to this end I provide a lower set of props or timbers 8 that are interposed between the mine floor 9 and the under face of the middleman 7, and supported above and in transverse alignment with these props 8 I provide an upper set of 10 props or timbers 10 preferably set exactly above the lower timbers and resting on the upper surface of the middleman and acting to support the roof 11. The timbering or roof supports employed may be of any suitable character, those shown being of a type that I consider best suited for such duty, but inasmuch as such mine supports form the subject matter of a companion application they are illustrated herein merely to serve as 20 a conventional showing for a suitable mine timbering that will carry the imposed load and protect the men and machinery at the faces.

I show conventional machinery for mining the coal at each level, the drawings illustrating a compressed air pick or drill 12 which the miner will manipulate so as to break down the coal and cause it to fall upon the adjacent conveyor section. Each conveyor 30 or section comprises a base plate 13 adapted to be advanced with its forward edge close to the face and with its rear edge 14 upturned to prevent the coal falling behind it and as a protection to the miner and enabling 35 him also to stand nearer the face. Over these plates works an endless conveyor comprising side chains 15 and cross bars forming conveyor blades 16.

The plate 13 on top of the middleman over- 40 hangs therefrom at each side into the mine entires or haulage ways 17 and 18, its delivery end passing over a drive sprocket 19 into position to deliver the coal mined above the middleman into the cars 20 in the entry 18. The return flight of the conveyor is carried down the upturned ends 21 of the lower plate 13 and travels thence along the bottom 45 of the face of the coal seam 6 under the middleman with its delivery end traveling up over the discharge end 22 of the lower plate 13 from which the coal is delivered into mine cars 23 in the entry 17. The conveyor passes 50 thence around the idler 24 and returns in continuous flight along the upper plate 13 so that, as shown in Fig. 2, its upper flight moves to the left above the middleman and loads cars 20 and its lower flight moves to the right below the middleman and loads cars 23.

The upturned ends 21 and 22 carry side 55 hold-down guides 28 which extend up to and are braced by members 29 to the overhanging ends of the upper plate 13. The bearings, not shown, for the idler 24, pulley 27 and sprocket 19 are supported by the braced ends 60 of the conveyor plates 13, and either or both

bearings may be adjusted to take up slack in the conveyor chain.

A motor 25 drives through a suitable gear reduction train, the belt 26 which in turn drives a large pulley 27 which actuates the 70 sprocket 19 to drive the endless conveyor.

As the mining proceeds, the timbering advances, making approximately equal progress above and below the middleman so as to keep the upper and lower sets of timbers in substantially superposed relationship. As the timbers are thus advanced they have unsupported behind them the roof and middleman and both of these in due course will subside in the manner well understood in mining 80 practice.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim is:—

1. The herein described method of mining mineral seams separated by interposed strata of waste material, which consists in supporting both the strata and the mine roof adjacent to the working faces of the seams so as to hold them in relative position until ready for them to subside together, and conveying the mineral mined above the strata in one direction to the loading point and conveying the mineral mined below the strata in the opposite direction to a different loading point.

2. The herein described method of mining, which consists in providing a mineral face to be worked between substantially parallel haulage ways, supporting a rock parting between seams of the mineral to be mined adjacent to the faces being worked so as to form a floor for the upper seam, advancing the supports for the parting and mine roof above it together so that the roof and parting can subside together behind the workings, and passing an endless conveyor about the parting so as to convey the mined mineral above the parting to the haulage way at one side and the mineral mined below the parting to the haulage way at the other side.

3. In a mining operation, the combination with superposed sets of timbers having a thick fault or parting in the seam left interposed between upper and lower sets of timbers which are adapted to support both the fault and the roof above the fault, of an endless conveyor passing around the fault 125 and adapted to move parallel with and adjacent to the faces being worked to discharge mineral by its upper flight at one side of the fault and by its lower flight to the other side of the fault, and haulage means at each side 130

of the fault to receive the mineral conveyed thereto.

4. The method of mining mineral lying in seams having a substantial parting therebetween, which consists in working the several mineral seams so as to keep their working faces in substantial vertical relationship with each other, providing along each working face a series of roof supports, moving

10 said supports to follow the advance of the

working face while maintaining said roof supports at the several levels in substantial vertical relationship, disposing a long wall conveyor close enough to each working face to receive the mineral as mined and moving it to follow the receding working face, and permitting the roof or parting above each series of supports to subside of its own accord as the work progresses.
